W. J. KNOX.

UNCOUPLING RIGGING.

APPLICATION FILED AUG. 26, 1914.

1,123,554.

Patented Jan. 5, 1915.

UNITED STATES PATENT OFFICE.

WILLIAM J. KNOX, OF DUBOIS, PENNSYLVANIA, ASSIGNOR TO WALTER P. MURPHY,
OF CHICAGO, ILLINOIS.

UNCOUPLING-RIGGING.

1,123,554.

Specification of Letters Patent.

Patented Jan. 5, 1915.

Original application filed April 29, 1911, Serial No. 624,176. Divided and this application filed August 26, 1914. Serial No. 355,688.

To all whom it may concern:

Be it known that I, WILLIAM J. KNOX, a citizen of the United States of America, residing at Dubois, in the county of Clearfield and State of Pennsylvania, have invented certain new and useful Improvements in Uncoupling-Riggings, of which the following is a specification.

This application is a division of my application filed April 29, 1911, Serial No. 624,176.

The primary objects of my invention are; the provision of an improved positive form of flexible connection wherein the use of chains, loose links and similar devices are avoided in an uncoupling rigging for car couplers; an uncoupling rigging which may be operated from either side of the car and in which the connections are entirely flexible and the parts secured against accidental displacement; and with these and further objects in view my invention consists of the parts and combination of parts as will be more fully hereinafter set forth.

25 In the drawings Figure 1 is a top plan view of a part of a car with my improved rigging in place thereon, Fig. 2 is a front elevation of the same.

The reference numeral 1 designates the 30 end of a car, 2 the coupler head and 3 the pin of the coupler.

Brackets 4 are secured to the end of the car, on opposite sides of the coupler, which are provided with a journal 5. The brackets are further provided with a laterally extending arm 6 on the end of which are outwardly extending stop flanges 7 and 8, stop flange 8 being inclined upwardly toward the end of the arm 6 so that a flaring space is 40 formed between said flanges as clearly seen in Fig. 2. 9 is a cotter pin passing through said stop flanges and serving as a guide for the operating lever.

The operating lever 10 is pivoted on the 45 journal and secured thereon by means of a nut as shown. The operating levers 10 and 11 are thus pivoted to the end of the car for vertical movement in the plane of the end of the car. Each operating lever 10 and 11 is 50 provided with a laterally bent portion intermediate its pivot and the inner end, the extreme inner end portion extending parallel with the main body portion of the lever.

A rock shaft 12 is supported on a pair

of brackets 13 which are secured to the end 55 of the car; said rock shaft being provided with forwardly extending arms 14 and 15 on either side of the coupler and overlie the inner ends of the operating levers 10 and 11. The arm 14 is downwardly deflected as at 60 15 and thence extended forward as at 16 in a substantially horizontal plane and thence bent laterally to form a bearing 17.

The pin lifting lever comprises a relatively long arm and a relatively short depending arm or loop 19 which is secured to the bearing 17 thus constituting a flexible connection between the rock shaft and the pin lifting lever, the longer arm overlying and having a floating bearing on the portion 16 of the arm 14.

The inner end of the longer arm passes through the eye of the pin 3 and terminates in a hook 20.

From the above it will be seen that by 75 this arrangement and construction of parts the locking pin 3 of the coupler may be operated from either side of the car and that an entirely flexible connection is provided, and that the parts cannot become accidentally displaced.

The outer ends of the levers 10 and 11 are provided with arms 41 extending under the car, adapted to be operated either by hand or the foot of the operator.

I claim:

1. In an uncoupling device for car couplers, the combination with a rock shaft mounted on the end of a car adjacent the coupler and provided with an outwardly extending lifting arm, a pin lifting lever flexibly connected at one end to said arm, the body portion of the pin lifting lever resting and having a floating bearing upon said lifting arm, of an operating lever pivoted to the end of a car for vertical movement in the plane of said end with its inner end underlying the lifting arm of the rock shaft and co-operating therewith for the purpose set forth.

2. In an uncoupling device for car couplings, the combination with a rock shaft mounted on the end of a car adjacent the coupler, a forwardly extending arm at each end of shaft, a pin lifting lever having a 105 flexible engagement with one of said arms of the rock shaft, the body portion of the pin lever resting and having a floating bear-

ing upon the body portion of the same arm, of operating levers pivoted near each side of the car on opposite sides of the coupler for vertical movement in the plane of the end of the car underlying and engaging the arms of the rock shaft, and coöperating therewith for the purpose set forth.

In testimony whereof I affix my signature in presence of two witnesses.

WILLIAM J. KNOX.

Witnesses:

HARRY J. SMITH,
ELBERT A. GARRISON.
